SLUSH PUMP VALVE

**Albert R. Steirly, Rockport, Tex.; Lois Steirly
Rozzell administratrix of said Albert R. Steirly,
deceased**

Application April 5, 1945, Serial No. 586,744
8 Claims. (Cl. 251—125)

In the rotary method of drilling the abrasive slush or mud is circulated down into the well bore and returned to the surface, and the pumps to effect this circulation are subjected to abrasive action due to the material of the fluid on one hand, and the valves in part to excessive pressures. Various types of slush pump valves have been devised with a view of maintaining a seal on the one hand, and absorbing the shock of the closing of the valve on the other hand. Very often these slush pump valves are of a size where they may have forty or fifty square inches exposed to the pressure when the valve is closing, so that if the pump is maintaining a pressure of one-thousand pounds per square inch, it is clear that each valve must take a rap of forty or fifty-thousand pounds each time it comes to a stop in its closing movement.

The present invention directs itself to a slush pump valve assembly which can be readily inserted and removed through the pump deck, and wherein the shock of stopping the valve in its closing movement is absorbed at one location while the sealing of the valve is accomplished at another location.

It is one of the objects of the invention to provide a stopping assembly for slush pump valves which is removably positioned upon the pump deck.

Another object of the invention is to provide a valve stopping plate which is removably supported above the pump deck and arranged to act as a stop for the downward movement of the slush pump valve.

Still another object of the invention is to provide a stop for a slush pump valve having a stem where the stop is spaced above the pump deck and adjustably anchored in position.

Still another object of the invention is to provide a slush pump valve having a stop ring on the upper end of the valve stem in combination with a stop plate therefor.

Another object of the invention is to provide a stop cage for slush pump valves which also serves as an outlet for the liquid being pumped.

Still another object of the invention is to provide an adjustable stopping collar for slush pump valves so that the position at which the valve is stopped may be adjusted to obtain the proper sealing action or to compensate for wear.

Other and further objects of the invention will be readily apparent with the following description is considered in connection with the accompanying drawings wherein:

Fig. 1 is a vertical sectional view of a portion

and the *Chlorophyceae* are the only groups which have been definitely demonstrated to be of algal origin. The *Chlorophyceae* are the only group which has been definitely demonstrated to be of algal origin.

PATENT OFFICE

6,927 **COMP. VALVE**

port, Tex.; Lois Steirly of said Albert R. Steirly,

945, Serial No. 586,744

Cl. 251—127) 2

of a pump showing the pump deck and the slush pump valve assembly in operative position therein;

Fig. 2 is a section taken on the line 2-2 of Fig. 1.

The pump 2 is provided with an outlet chamber 3 from one of the reciprocating pistons, and this chamber is closed by a pump deck 4 having a tapered seat 5 to receive the slush pump valve seat ring 6. This ring in turn has the annular passage 7 therethrough and a spider thereacross to support the guide hub 8 for the stem 9 of the slush pump valve 10.

The outlet chamber 11 above the pump deck 4 is defined by the top 12 of the pump, and a port-hole 13 is closed by the pot cover 14 held in place by the bolts 15 on the nuts 16. The slush pump valve 10 may be of any desired construction, but is preferably that of my prior copending application, Serial No. 523,813, filed February 25, 1944, now abandoned, for a slush pump valve.

This valve includes a body 20 having the stem 9 projecting through the opening 21 in the hub 8 where it is guided by the resilient wear rings 22. The flange 24 of the body supports the valve.

22. The flange 24 of the body supports the resilient sealing ring 25, and it is arranged to engage the curved seating surface 26 on the top of the seat ring. The hold-down plates 27 and 28 hold this resilient ring in position on the upwardly projecting stem 30. This stem 30 is threaded at 31 on its upper end with a cross thread arranged to adjustably receive the stop collar 32. This collar can be set in any desired position on the stem 30 by the locking bolt 33.

To receive the stop collar 32 and limit the downward movement of the valve 20 so as to protect the resilient seal ring 25, there has been provided a stop plate 35 having an opening 36 therein which receives the stop gasket 37 which is disposed in a recess 38 in the stop plate 35 so as to confine it against extrusion due to the pressure from the stop collar 32.

A cage or ring 40 which is cylindrical in configuration, rests upon the surface 41 of the pump deck 4 and encloses the seat ring 6 and the slush pump valve so as to provide a working chamber 42 from which the liquid being pumped may flow through the discharge outlets 43. The plate 35 seats in the recess 44. The cage 40 may be formed as desired, but to insert it through the opening 30, there has been made a plurality of parts such as 47 and 48 which may be segments of a circle. These segments may be passed through the opening 13 and inserted or inter-

locked by the tongue and groove construction 49, best seen in Fig. 2. When all assembled, these segments make a complete ring or cage which serves to support the stop ring 35.

In order to retain the stop plate in position on the substructure of the valve and to also provide a stop for the valve on its upward movement, a bridge, or cap 50 in the form of an inverted cup is shown as disposed on the upper surface 51 of the stop plate 35. This cap encloses the 10 adjustable stop ring 32 and is intended to prevent abrasive material from entering the chamber formed by the cap and the stop plate.

In order to firmly anchor the stop plate in position, an adjusting spindle 53 is threaded at 15 54 through the pot cover 14. In this manner the parts may be assembled, the pot cover firmly anchored, and then the spindle 53 adjusted to firmly anchor the cap.

Broadly the invention contemplates a slush pump valve assembly where the stopping mechanism is separated from the sealing area, and where adjustment may be made to control the point where the valve will be stopped without interfering with the valve. 20

What is claimed is:

1. A slush pump valve assembly including a valve body, a valve seat in the valve body, a valve to engage said seat, a stem on said valve, a valve stopping assembly on the valve body including a support ring supported on a surface contiguous with said seat, a plate thereon thru which said valve stem projects, a head on said stem, and a top member on said plate disposed to stop said head. 25

2. A slush pump valve assembly including a valve body, a valve seat in the valve body, a valve to engage said seat, a stem on said valve, a valve stopping assembly on the valve body including a support ring surrounding said valve and supported on a surface contiguous with said seat, a plate thereon thru which said valve stem projects, a head on said stem, a stop member on said plate disposed to stop said head, a pot cover and means carried by the pump pot cover and engaging said plate to hold said plate in position. 30

3. A slush pump valve assembly including a valve body, a valve seat in the valve body, a valve to engage said seat, a stem on said valve, a valve stopping assembly on the valve body including a support ring supported on a surface contiguous with said seat, a plate thereon thru which said valve stem projects, a head on said stem, and a stop member on said plate disposed to stop said head, said ring having a plurality of outlet ports 35 therethrough. 55

4. A slush pump valve assembly including a valve body, a valve seat in the valve body, a valve to engage said seat, a stem on said valve, a valve stopping assembly on the valve body including a support ring, a plate thereon thru which said valve stem projects, a head on said stem, and a stop member on said plate disposed to stop said head, comprising an adjustable nut to set the stopping position of said valve.

5. A slush pump valve and stopping device therefor comprising a valve having a stem, a stop head adjustably carried by said stem, said stopping device including a stop cylinder enclosing said valve, a stop bridge thereon, and means on said bridge to receive said head. 10

6. A slush pump valve and stopping device therefor comprising a valve having a stem, a stop head adjustably carried by said stem, said stopping device including a stop cylinder enclosing said valve, a stop bridge thereon, means on said bridge to receive said head, and a cap disposed on said bridge to enclose said head and means. 15

7. A slush pump valve and stopping device therefor comprising a valve having a stem, a stop head adjustably carried by said stem, said stopping device including a stop cylinder, a stop bridge thereon, means on said bridge to receive said head, a cap disposed on said bridge to enclose said head and means, and means including a stud to hold said cap in position on said bridge. 20

8. A slush pump valve and stopping device therefor comprising a valve having a stem, a stop head adjustably carried by said stem, said stopping device including a stop cylinder enclosing said valve, a stop bridge thereon, and means on said bridge to receive said head; said stop cylinder including a plurality of interlocking parts. 30
